UNITED STATES PATENT OFFICE.

HUGH MOORE, OF EASTON, PENNSYLVANIA, ASSIGNOR TO INDIVIDUAL DRINKING CUP COMPANY, INC., OF EASTON, PENNSYLVANIA, A CORPORATION OF PENNSYLVANIA.

PAPER-CUP AND CUP-DISPENSER SHIPPING PACKAGE.

Application filed January 19, 1928. Serial No. 247,937.

This invention relates to an improved paper cup and cup dispenser shipping package.

The invention comprehends a paper cup and cup dispenser shipping package comprising a number of cartons of nested paper cups and a dispenser device or member which is adapted to be employed with the cup cartons to dispense the cups directly therefrom.

An object of the invention is to provide an improved shipping package of the character referred to in which the dispenser device or member is arranged with the cartons of nested cups to occupy minimum space and to readily form with the cartons of cups a close pack of regular form in a single shipping case or container of regular conventional form convenient for handling and shipping.

A further object of the invention is to provide for the packing of the cup cartons and the dispenser device or member in a single package and with the dispenser device or member assembled or interfitting with one of the cup cartons to indicate in a simple way the manner in which the dispenser device or member is adapted to be employed with the cup cartons to dispense the cups therefrom.

The invention, with other objects and advantages thereof, and the particular construction, combination and arrangement of parts comprising the same, will be understood from the hereinafter contained detailed description when considered in connection with the accompanying drawings forming part hereof and illustrating one embodiment of the invention.

In the drawings:

Figure 1 is a perspective view of a paper cup and dispenser device shipping package in accordance with the present invention.

Fig. 2 is a longitudinal section.

Fig. 3 is a transverse section.

Fig. 4 is a detail side elevation of one of the cup cartons.

Fig. 5 is a side elevation with one of the cup cartons seated in the dispenser device.

Fig. 6 is a vertical section of one of the cartons and dispenser device assembled as shown in Figure 5.

Fig. 7 is a horizontal section on the line 7-7 of Figure 6.

While a specific embodiment of the invention is illustrated in the drawings, it will of course be understood, that changes and

obvious modifications may be made in the particular construction and arrangement of parts shown, and the invention carried out in other forms, as will appeal to those skilled in the art and falling within the scope of the appended claims, without departing from the spirit of the invention.

Referring to a detailed description of the particular embodiment of the invention shown in the drawings. A designates a conventional form of carton for marketing paper cups, the same being rectangular shaped in cross section, provided with closure flaps 1 at one end thereof, and adapted to contain a stack of nested cups designated 2. The form of cup shown is a well known construction of paper cup having an outwardly extending flange at the top, the rim flanges of the cups being spaced, as shown, when the cups are nested.

B designates a dispenser device or member adapted to cooperate with the carton A to support the same and to provide for dispensing cups directly therefrom. The dispenser device or member B is in the form of a tubular part or casing of metal, square shape and substantially the same size and cross section as the cup cartons A.

The dispenser device or member B is adapted to be secured in a vertical position to any suitable support, by suitable means for instance screws 3 passing through openings in the rear wall thereof, as illustrated in Figure 7 of the drawings. The dispenser device or member B is adapted to have detachably seated within its upper part a cup carton A, the interior diameter of the dispensed device or member B corresponding to the diameter of the cup carton A and being provided with shoulders 4 for the lower end of the carton to rest upon. Below the shoulders 4 the dispenser device or member B is provided with cup retaining and separating means comprising inwardly extending transverse ledges 5.

When the carton A is inserted in the dispenser device or member B, the end flaps 1 of the carton having been first removed, the stack of cups 2 is supported by the retaining and supporting ledges 5, the cups 2 being withdrawn one by one from the carton A and dispenser device B by a downward pull upon the lowermost of the stack of nested cups resting upon the retaining ledges 5.

In accordance with the present invention a number of the cartons A of nested cups and one of the dispenser devices or members B, which, as hereinbefore explained, is adapted to be used with the cartons, are arranged together in a single shipping case or container. C designates a shipping case or container of conventional rectangular form, the same being here shown as constructed of paper board and provided with closure flaps 6 at one end. In accordance with the present invention the shipping case or container has an interior area relative to the size and dimensions of the cup cartons A so that a given number of said cartons will fill said area and be snugly held in place. One of the cartons of the package is cut off or shorter with respect to the other cartons and fitted into the upper part of the dispenser device or member B in operative relation therewith and to present with the dispenser device or member a shape and length corresponding to the length of the full length cartons. In the drawings, reference being had particularly to Figures 1, 2 and 3 thereof, A' designates the carton of reduced length having the upper part of the dispenser device or member B telescoped with an end portion thereof. The shorter carton A' with the dispenser device or member B fitting thereover is arranged side by side with the other full length cartons A in a close pack, as shown, within the shipping case or container C. In the particular construction shown the cup cartons are arranged in rows transversely of the shipping case, the shorter carton A' with the dispenser device or member B fitting thereover being shown arranged in the end row of cartons disposed at that end of the shipping case having the closure flaps 6 providing for access to the case to be in plain view when the carton is opened.

It will be noted that the invention provides a shipping package comprising a number of the cartons of nested cups and a dispenser device for use therewith, the dispenser device being arranged with the cartons to occupy a minimum space and to form therewith a close pack of regular formation snugly fitting and held in a single shipping case or container, the latter being of regular conventional rectangular shape convenient for handling and shipping. The improved package provides for a very economical and satisfac-

tory distribution of a number of cartons of nested cups and a dispenser device for use therewith. The necessity for a separate package for the dispenser device is avoided and the association of the dispenser device in operative relation in the package with one of the cartons, serves to indicate quickly to the dealer the manner in which the dispenser device is adapted to be employed with the cartons of nested cups.

The particular construction of dispenser described and shown in this application but not claimed, forms the subject matter of my copending application Serial No. 152,885.

What I claim is:

1. A paper cup and cup dispenser shipping package comprising a shipping case containing a number of cartons of nested paper cups and a dispenser device, the interior area of the shipping case and the cartons being of relative size and dimensions so that a given number of said cartons will fill said area and be snugly held in place, one of said cartons being cut off or shorter with respect to the remaining cartons and combined with said dispenser device to present a completed size and shape corresponding to the size and shape of the full length cartons, the dispenser device being tubular and detachably connected with an end portion of the shortened cup carton to enable removal and discarding of the latter when emptied and substitution of any of the other filled cartons.

2. A paper cup and cup dispenser package comprising a rectangular shaped shipping case containing a number of cartons of nested paper cups and a dispenser device, the cartons being square shape in cross section, and the interior area of the shipping case and the cartons being of relative size so that a given number of said cartons will fill said area and be snugly held in place, said dispenser device being square shape in cross section and one of the cartons being shorter with respect to the remaining cartons and detachably fitting into the dispenser device in operative relation therewith and to present therewith a length corresponding to that of the full length cartons.

In testimony whereof I hereunto affix my signature.

HUGH MOORE.
